UNITED STATES PATENT OFFICE.

WALTER B. SO RELLE, OF NEW YORK, N. Y., ASSIGNOR TO YARDSMORE GOLF CLUB MANUFACTURING COMPANY, OF NEW YORK, N. Y., A CORPORATION OF DELAWARE.

GAME CLUB.

Application filed June 8, 1923. Serial No. 644,072.

This invention relates to game clubs and has for its object to provide improved means for retaining striking inserts in place and at the same time to shape them so as to 5 make certain of driving the ball in the intended direction.

Various types of inserts have been suggested for the striking face of game clubs, such as a golf driver or brassie, polo mallet, 10 etc. The impact of the ball upon the elastic insert causes considerable momentary distortion and flexure, which, while not appreciable to the eye, nevertheless tends to loosen the insert. When the ball hits the edge of 15 the insert the distortion thereof may not be uniform and may impart a wrong direction to the ball. The elastic insert in a golf club, for example, cannot be put in place from the rear of the striking face because of 20 the presence of the counterweight in this part of the club head and in order that the impact from the insert shall not be transmitted to the counterweight and loosen the same, it is desirable to have a substantial 25 thickness of wood or other material between the insert and the weight. When, therefore, the inserts must be positioned from the striking face it will be seen that the problem of retaining them securely in position is 30 more difficult than if they could be inserted from the rear.

According to this invention some of these disadvantages are overcome not only by making the width of the insert greater, but 35 more especially by reinforcing the sides and giving them an outward taper from an enlarged base toward the striking face whereby the force of impact with the ball is taken up by the enlarged body of material making 40 up the insert, resulting in less distortion and loosening. The foundation is enlarged resulting in the stresses within the insert, which are not taken up by the body being distributed over a large contact area with 45 the wood or other material of the club head. The insert of this invention is made in several parts with the axis of at least one part angularly disposed to that of another in order to exert a wedging action and prevent 50 the several parts working loose.

Specifically a central insert of cylindrical or other substantially uniform cross section is located in cut away portions of lateral inserts which are preferably longer than the 55 central insert to partially provide founda-

tion therefor and which are angularly arranged to diverge from the striking face whereby a wedging action is obtained and the several parts of the insert function as a large single insert to take up the stresses 60 within the material.

Referring to the drawings:

Figure 1 is a side view of the golf club having the insert of this invention embodied in its striking face, 65

Fig. 2 is a section on the line 2^a—2^a of Fig. 3,

Fig. 3 is a horizontal section on the line 3^a—3^a of Fig. 1,

Fig. 4 is a view corresponding to Fig. 1 70 but showing another embodiment of this invention,

Fig. 5 is a section on the line 5^a—5^a of Fig. 7,

Fig. 6 is a section on the line 6^a—6^a of Fig. 4, and

Fig. 7 is a section on the line 7^a—7^a of Fig. 5.

For the sake of illustration this invention has been shown embodied in a wooden golf 80 club such as a driver 10 having a striking face 11 containing an insert 12 of elastic material such as galalith, or ivory, for example. The bottom of the club is provided with the customary metal plate 13, while the 85 rear face contains the usual counterweight 14 for obtaining the proper balance.

The insert shown in Figs. 1 to 3 comprises a central insert 15 having on each side thereof lateral inserts 16 and 17 which 90 are longer than the central insert, arranged with their axes diverging from the striking face and grooved to cooperate with the central insert in the manner shown. These lateral inserts not only provide additional 95 width for the striking face but by reason of their angular disposition provide an increase in the body of the insert which is effective to take up impact strains within the insert and transmit less of these strains 100 to the material of the club head. The enlarged base for the insert is effective to more uniformly distribute the remaining stresses imparted to the club head over a larger area. The end walls 18 of the grooves 105 in the lateral inserts provide a foundation for the central insert inasmuch as the lateral inserts are of greater length. To help retain each insert in position they are provided with cavities 19 near the base adapted 110

to contain cementitious material, or glue. As a means for making a stronger connection, a channel 20 in each insert may contain a strip of the cementitious material 5 connecting the cavity 19 with the body of such material at the base of said inserts. The grooves in the lateral inserts 16 and 17 may be preformed before such inserts are cemented in position, but preferably these 10 lateral inserts are fixed in position before the hole is drilled for the central insert 15 whereby upon driving the central insert in position it is effective to exert a wedging action to retain the lateral inserts in place. 15 As shown, the central insert 15 comprises an inner insert 21 of the same material, which may be of a different color to provide an attractive appearance, and in the same manner the lateral inserts 16 and 17 may be 20 the same or of different colors, if desired.

In the embodiment illustrated in Figs. 4 to 7 the central insert is grooved to receive a plurality of smaller lateral inserts 22, 23, 24 and 25 which are also angularly disposed 25 with their axes diverging from the striking face. Here again each insert may be similarly provided with cementitious cavities 19 and grooves 20 in order to more firmly retain them in position. The central insert 30 is inserted in position and the angularly arranged holes are then drilled for the lateral inserts 22 to 25. It will be seen that in this embodiment also the several inserts cooperate to provide the wedging action for 35 surely being retained in position.

Among the advantages of this invention may be mentioned the substantially dovetail cross section to the insert as shown in Fig. 3, whereby the increasing width to the material behind the striking face is effective to take up the shocks of impact within 40

the material and transmit less stress to the material of the club head with the result that less distortion and loosening of the insert is present than occurs with those inserts having substantially parallel sides. 45 Another feature is the wedging action exerted by one insert upon another whereby both are retained in position. The use of cementitious material in the cavities and 50 grooves near the base of the inserts helps to firmly position the insert. The enlarged base is effective in transmitting the impact stresses over a larger area. The provision of the central insert 15 with a foundation 55 in each of the lateral elastic inserts in another feature helping to have the impact shocks taken up within the body of elastic material and less imparted to the material 60 of the club head.

I claim:

1. A game club having an insert in its striking face, which insert has a central section provided with a base of larger area than the area of the insert on the striking 65 face and which comprises a plurality of angularly disposed inserts arranged to provide a wedging action adapted to retain them in position, one of said inserts being grooved for cooperation with another, and 70 a cementitious material for retaining said inserts in position.

2. A game club having an insert in its striking face provided with a retaining cavity for cementitious material near the base 75 thereof and a connecting groove for said material extending from said cavity to the base.

Signed at New York city in the county 80 of New York and State of New York this 7th day of June A. D. 1923.

WALTER B. SO RELLE.
